[57] CLAIM

The ornamental design for a thread nipper, as shown and described.

DESCRIPTION

FIG. 1 is a side elevational view of a thread nipper showing our new design;

FIG. 2 is an end view as seen from the left of FIG. 1;

FIG. 3 is a top plan view thereof;

FIG. 4 is an end view as seen from the right of FIG. 1;

FIG. 5 is a side elevational view of the thread nipper from the side opposite to that shown in FIG. 1; and

FIG. 6 is a bottom plan view thereof, being opposite to the view shown in FIG. 3.
